UNITED STATES PATENT OFFICE.

JOHN W. OLSON, OF MAQUON, ILLINOIS, ASSIGNOR TO SOLOMON C. DENNIS
AND JAMES E. DENNIS, BOTH OF SAME PLACE.

WAGON END-GATE.

SPECIFICATION forming part of Letters Patent No. 366,734, dated July 19, 1857.

Application filed January 26, 1866. Serial No. 189,847. (No model.)

To all whom it may concern:

Be it known that I, JOHN W. OLSON, a citizen of the United States, residing at Maquon, in the county of Knox and State of Illinois, 5 have invented certain new and useful Improvements in Combined Wagon End-Gate and Shoveling-Board, of which the following is a specification.

My invention relates to that class of end-gates for wagons which can be turned down to make a shoveling or scoop board.

My improvements consist in certain details of construction and combinations of parts pertaining, first, to the means of securing the 15 standards of the end-gate to the side-boards of a wagon of the usual construction; second, to the mode of hinging the end-gate to the standards, and, third, to the improved hinged connection of the end-gate, together with novel 20 means for holding the bottom of the end gate closely against the bottom of the wagon with an elastic pressure when the end-gate is dropped to its inclined position as a scoop-board.

25 In the accompanying drawings, Figure 1 is a perspective of the rear end of a wagon-body with my improved end-gate applied thereto in its closed position as an end-gate; Fig. 2, a similar view of the same with the end-gate 30 dropped to its inclined position as a scoop-board; Fig. 3, a sectional elevation of the rear end of a wagon with my improved end-gate applied thereto; Fig. 4, a horizontal sectional plan of one corner of the wagon in the line x 35 x of Fig. 3 and one end of the end-gate to show their mode of construction; Fig. 5, a sectional elevation similar to that shown by Fig. 3, but with the end-gate turned down as a shoveling-board or scoop-board.

40 The improved device is shown as applied to a wagon-body of ordinary construction, with sides A and bottom A', and with cleats a secured to the inner sides and rear ends of the body and arranged parallel with each other 45 to form grooves for the reception of the ordinary end-gate. The end-gate standards B are provided with guide-ribs B', which snugly fit and slide between the cleats a of the side-boards of the wagon-body, and are also provided 50 with guide-rails B'', which overlie the outer side of the said side-boards and serve to

hold the guide-ribs B' securely in the groove between the cleats a and admit of their vertical sliding movement therein for the removal or replacement of the standards from or upon 55 the end of the wagon-box.

The lower ends of the standards B are squared out or stepped out at b to rest firmly upon the floor of the wagon-box and to project below the said floor at b' , and a tie-rod, C, passes 60 through the projections b' , and extends from one standard to the other parallel with and slightly in rear of the end of the wagon-box floor. A segmental slot, b'' , is formed in the lower end of the standards, which forms a part 65 of the hinged connections between the end-gate and standards, as will hereinafter appear.

The end-gate D rests at its lower end upon the rear end of the floor of the wagon-box and is hinged to the lower ends of the standards 70 B by pintles d , which project therefrom and pass through the segmental slots b'' , formed in the lower ends of the standards, hereinbefore described.

The end-gate D is provided with fixed side 75 pieces, D', of any preferred shape or size, to prevent the discharge of material from the sides of the gate in a well-known manner, and is also provided with metal cross bars or cleats D'' D'', riveted securely to the rear side thereof 80 to strengthen it. The cleat D'' is formed with bolt-holes d' in its projecting ends, through which rods F, secured by eye bolts F' to the upper ends of the standards B, pass and are permitted to move endwise freely therein, and 85 heads F'' on the ends of the rods F support the end-gate D in its inclined position. (Shown in Figs. 2 and 5 of the drawings.)

When the end-gate is raised to its vertical or closed position, (shown in Figs. 1 and 3,) the 90 rods F pass entirely through the holes d' , and the eyebolts F' also pass into and partly through the said holes d' to permit the rods F to drop or swing down behind the end-gate and inside the tie-rod C to lock and hold the 95 gate at both its upper and lower ends securely to the standards. The rods F are securely held down by the tie-rod C, and must be first swung across or transversely to the end of the wagon to clear the tie-rod C before they can 100 be swung upwardly to pass freely through the holes in the end of the cleat D'' to unlock the

end-gate and permit it to drop into its inclined position, as hereinbefore described. When the end-gate is lowered or swung down to its inclined position, its upper end will be supported by the rods F, and the spring-plate E will bear beneath the under side of the floor of the wagon-box with an elastic pressure to hold the lower end of the end-gate in close contact with the floor and prevent the escape of grain therefrom, and the lower end of the gate will rest upon and be supported by the tie-rod C and by the pintles d, which rest in the outer ends of the segmental slots b², formed in the lower ends of the standards. The spring 15 stop-plate E, together with the tie rod C, thus serves to hold the lower end of the end-gate when in its lowered position as a scoop-board, and will serve as a safety-stop to hold up the lower end of the gate should the hinge-pintles 20 d become broken. The standards, together with the end-gate, may be removed from the end of the wagon by sliding them upwardly between the cleats a a of the wagon-body as easily as an ordinary end-gate, and when not 25 desired for use it may be removed and the ordinary end-gate substituted therefor without change in the construction of either device, and may be readily replaced in the wagon-box, as the end-gate and standards B are connected, as herein described, with each other.

I claim as my invention and desire to secure by Letters Patent—

1. In a wagon-box, the standards B and tie-rod C, in combination with the end-gate provided with a spring stop-plate, E, located substantially as shown, and adapted to swing between the standards and be supported at its lower end by the stop-plate, substantially as described.

40 2. The combination of the standards B, pro-

vided with segmental slots in their lower ends, with an end-gate provided with spring stop-plate E, pintles d, to support the lower end of said end-gate, and rods F, hinged or swiveled to the standards to support the upper end 45 of the end-gate, substantially as described.

3. The combination of the standards B with an end-gate loosely hinged thereto at its lower end, and provided with a spring stop-plate, E, adapted to hold the bottom of the gate with a 50 yielding pressure upon the floor of the wagon-box, substantially as described.

4. In a wagon end-gate and scoop-board, in combination, standards with ribs B' and rails B², end-gate D, hinged, as described, to said standards, spring stop-plate E, and rods F, hinged to the standards, passed through the bar D², and provided with a head which supports the end-gate as a scoop-board, substantially as and for the purpose specified.

5. In combination, the standards with ribs B', end-gate hinged, as described, to said standards and provided with side-boards fixedly connected therewith, and rods F, hinged to the standards, passed through the bar D², and provided with a head which supports the end-gate as a scoop-board, and the spring stop-plate, substantially as and for the purpose specified.

6. In combination, the standards with ribs B' and guide-rail B², end-gate hinged, as described, to said standards, and provided with side-boards fixedly connected therewith, and the spring stop-plate E, substantially as and for the purpose specified.

In testimony whereof I affix my signature in presence of two witnesses.

JOHN W. OLSON.
